UNITED STATES PATENT OFFICE.

JACOB VICKERY LANGHORNE, OF ENGLEWOOD, COLORADO, ASSIGNOR OF ONE-HALF TO
SEABORN M. BATTON, OF DENVER, COLORADO.

RECEPTACLE-CLOSURE.

1,265,095.

Specification of Letters Patent.

Patented May 7, 1918.

Application filed June 4, 1917. Serial No. 172,691.

To all whom it may concern:

Be it known that I, JACOB VICKERY LANGHORNE, a citizen of the United States, residing at Englewood, in the county of Arapahoe and State of Colorado, have invented certain new and useful Improvements in Receptacle-Closures; and I do hereby declare the following to be a full, clear, and exact description of the invention, such as will enable others skilled in the art to which it appertains to make and use the same.

This invention relates to improvements in receptacle closures, and it is primarily designed to provide a readily removable and replaceable cover, forming an air tight seal with the top of the can, jar or other analogous container, the contents of which, after the container has been first opened, it is desired to protect from continued exposure to the air, for obvious and varied reasons.

In its broad application, the invention may be applied to any suitable container, regardless of its particular class or the material of which it is composed, and regardless of whether it is adapted to package preserved foodstuffs, or non-edible compounds of a quasi-pasty or semi-liquid nature, such as pastes, paints, printers' inks, etc., which when exposed to the air for any considerable time, dry up or are formed with a skin or scum on their top surface, or are otherwise deleteriously affected by the exposure.

It will be understood at the outset, therefore, that my invention is not restricted in its application for use with any particular class of goods or containers therefor, but, for the purpose of brevity, in the following specification, I shall simply refer to one of its primary uses by way of illustration.

In packaging printers' inks for instance, the same is put up in various sized commercial tins or containers, which when initially opened expose the contents to the action of the surrounding atmosphere, unless suitably covered up against such exposure.

As before stated, such continued exposure to the air not only causes a diminution in quantity, owing to evaporation and the formation of a stiff scum or skin-like surface, which must be skimmed off as waste, but more important still it is also seriously deleterious to the very body and quality of the ink itself.

As the contents of these containers are

gradually drawn upon, at frequent intervals as necessity requires, instead of being entirely used up at one time, it becomes a very important factor to avoid such deterioration and waste thereof, and at the same time provide a proper closure for affording ready access to the inks.

Ordinary covers have not proven satisfactory, as they either permit of leakage of air into the container, or are so unhandy to remove or replace, that the user more generally leaves the container uncovered entirely, during use, rather than be bothered with removing and replacing the closure therefor. Besides this, considerable loss of time and annoyance are involved in the employment of a tight-fitting cover.

The primary object of the present invention, therefore, is to provide a suitable air tight closure, for such commercial containers, to avoid the objections mentioned, and one which at the same time is readily removable and replaceable, in the economic handling of the contents thereof.

Other objects and advantages will be apparent in connection with other classes of containers, such as the prevention of mold formation on preserved articles, after opening, or the emission of odors or gases from other contained substances or liquids, contained in a receptacle associated with my improved type of cover.

Having generally stated the objects and advantages of the invention, to more fully disclose the essential characteristics thereof, reference will now be had to the accompanying drawings, forming a part of this application, in which drawings like characters designate the same parts in the views, and in which:—

Figure 1, is a top plan view of my improved form of cover, and

Fig. 2, is a central vertical sectional view through the improved cover, and a part of a container as associated therewith.

It will be apparent that my improved closure may be composed of any suitable material or substance that can be shaped up in form and dimensions as may be desired to adapt it to the particular container or containers with which it is to be associated.

In the drawings, it is shown as composed of metal, and of hollow cylindrical formation, having a substantially deep peripheral

wall 1, an open bottom 2, and a top portion 3.

Within this hollow cover, spaced from the bottom opening 2 thereof, is suitably mounted a false bottom or partition 4, providing an upper compartment 5 and an annular lower space, in which latter there is disposed an annular gasket-like element or disk 6, to provide a cushioning air tight contacting surface with the top edge 7 of the container 8, the contents of which latter being indicated at 9.

This air tight contacting element 6 may obviously be in the nature of an annular flat surfaced ring, or a solid disk as shown, and may be composed of an oil treated paper or material, felt, rubber, rubber compound, or any other suitable composition or material, fitted for the particular usage to which it is to be put, and possessing a certain degree of pliable resiliency to insure an intimate seating contact with the top edge 7 of the receptacle.

In order to more practically insure this intimate contact, the element 6 is preferably provided with an underlay or pad 10 of blotting paper or similar pliable material, interposed between it and the underneath face of the false bottom or partition 4, to function as will be clearly understood.

The bottom opening 2 of the cover is of greater dimensions than the diameter of the receptacle to be covered, to provide for the more facile seating and removal of the cover, as is desired, and in the drawings, while the top edge of the receptacle is shown as being rolled over or crimped, it will be understood that my invention is equally applicable to the top of a can, the upper edge of which is of different formation, or which has been formed by an integral top to the can having been cut out to open same, as is frequently done.

The hollow cover is provided with an aperture for the introduction of a weighting substance or the like, of a variable quantitative value, within the interior of the upper compartment 5. A simple expedient is to provide a central boss 11, having a bore therethrough, which is preferably threaded to receive the screw-threaded shank of a knob 12, although it is apparent that I am not specifically restricted to this arrangement. This particular arrangement, however, would serve the dual purpose of enabling the compartment to be wholly or partly filled for weighting purposes, and also providing a handle for the cover.

Any suitable weighting substance or material may be used, which may be varied in quantity, such as sand, shot, etc., and for the purpose of illustration only, I have shown a quantity of shot 13.

It may also be stated that it is my aim to ship these hollow covers "light", or without

the weighting agency, which latter can be filled into the compartment 5, to the quantity desired, at the local place of use.

Also, when the improved cover is to be used with different colored inks, the knob 12 may be equivalently painted as black, red, etc., and serve as an indicator for the contained colored inks.

I am aware of the fact that barrels, large cans and similar receptacles, have heretofore been provided with hollow covers adapted to seat over the top edge of the receptacle loosely, with the underneath face of the cover resting on the top edge of the receptacle, and I make no claim to this broader idea, my invention particularly residing in the novelly combined improved cover, which makes it peculiarly adaptable for an airtight closure, substantially of the character described and for the purposes set forth.

Having thus fully disclosed the invention, it will be understood that I do not limit myself to the exact details as shown and described, the invention not being so restricted, excepting as embodied in the ensuing claims and a reasonable interpretation of the scope thereof, contemplating a fair range of equivalents.

What I do claim as new and patentable, is:—

1. A hollow cover, having a substantially deep peripheral wall, a closed top and an open bottom, the said peripheral wall being of slightly greater dimensions, in cross-section, than the top of the receptacle to be covered, in combination with an interiorly disposed flat false bottom, located equidistant, as a whole, at a substantially spaced position from the lower open end of said cover, and forming with the top thereof a substantially deep upper compartment; a flat pliable sealing disk associated with the underneath face of said false bottom, and adapted to engage the top edge of the receptacle, in a cushioning air-tight relation, while the lower peripheral wall of the cover envelops the top of the receptacle; and means in the upper part of the cover for introducing a variable weighting means within the said upper compartment, for holding said cover fixed against ordinary displacement, when seated, substantially as described.

2. A hollow cover, comprising an apertured closed top with a depending substantially deep peripheral wall open at its bottom and of slightly greater dimensions, in cross-section, than the top of the receptacle to be covered, in combination with an interiorly disposed flat false bottom located equidistant, as a whole, at a substantially spaced position from the lower open end of said cover and forming a substantially deep upper compartment with the closed top; a flat pliable sealing disk associated with the underneath face of said false bottom and

adapted to engage the top edge of the receptacle in a cushioning air-tight relation, while the lower peripheral wall envelops the top of said receptacle; a pliable underlay disk interposed between said sealing disk and false bottom; weighting means adapted to be introduced in a variable quantity into said upper compartment, for holding said cover

fixed against ordinary displacement, when seated; and a knob element functioning to close said apertured top, after filling, and also serve as a handle for said weighted cover, substantially as described.

In testimony whereof, I affix my signature.

JACOB VICKERY LANGHORNE.
